GARMENT

Tedi Barri Craig, Los Angeles, Calif., assignor of
one-half to James Craig, Los Angeles, Calif.

Application May 7, 1945, Serial No. 592,379

3 Claims. (Cl. 2—74)

1

This invention relates to garments and relates more particularly to dresses, or the like. An object of my invention is to provide a dress, or like garment, which is simple to construct, inexpensive to manufacture, and pleasing in appearance.

Although embodiments of my invention may be constructed of various fabrics such as wool, rayon or silk, I more particularly seek to provide a washable garment made of cotton or linen fabrics such as calico, seersucker, denim, lawn, etc., the primary object of my invention being to provide a washable garment which is easily and quickly ironed.

Another object of my invention is to provide a garment constructed in a manner whereby it can be ironed in a flat condition.

Another object of the invention is to provide a garment of such construction that it can be ironed in a mangle quickly, easily and without wrinkles.

Another object of the invention is to provide a garment without pleats or folds or with stitched down pleats or tucks whereby it can be economically manufactured and is pleasing in appearance when worn.

A further object of my invention is to provide a garment which is sewn together without open pleats, folds or ruffles, which can be readily ironed flat and without wrinkles, and which embodies means for drawing portions thereof together so that the garment fits the body of a wearer with a trim and pleasing effect.

A still further object of my invention is to provide a garment which is constructed in a flat condition and without regard to exact size or fit and which incorporates means for obtaining a nicety of fit on the body of the wearer.

A still further object of my invention is to provide a garment of the character indicated incorporating simple and effective means, which are also decorative, for conforming and fitting particularly the waistline, neckline, and sleeve ends to the person of the wearer after donning the garment.

The various objects and features of my invention will be more fully understood from the following detailed description of a typical, preferred form and application of the invention, throughout which description reference is made to the accompanying drawings, in which:

Fig. 1 is a front view of a dress incorporating the invention and shown in its normal flat unworn condition.

Fig. 2 is a similar view of said dress as it appears when worn and fitted to the person of the wearer.

2

Fig. 3 is a flat view of a fabric blank comprising the dress before sewing of the side seams, the view essentially depicting the pattern of the dress.

Fig. 4 is an enlarged cross sectional detail view as taken on the line 4—4 of Fig. 1, said view being typical of the construction at various points of the dress.

Fig. 5 is a similar view of a modified form of construction.

10 The garment I have chosen to illustrate as an embodiment of the invention is a dress which comprises generally, a fabric blank 10, tapes or the like 11, 12 and 13 stitched to said fabric blank along the front waistline, around the neckline, and along the sleeve ends, respectively, and draw or puckering strings or cords 14, 15 and 16 in pockets or channels formed by said tapes 11, 12 and 13, respectively.

I have shown the blank 10 as a single piece of 20 fabric. I wish it to be understood, however, that said blank can be made up of several component pieces to obtain various and pleasing effects particularly with fabrics having design configurations, stripes, etc. With striped fabric as an example, the portion of the blank 10 from the waistline down, both front and back, can have the stripes disposed in a different direction from the direction of the stripes on the main body of the blank. By such simple means the appearance of 30 the garment, generally, can be enhanced.

I show the blank 10 as comprising a dress front part 17 and an identical back part 18 having respective side edges 19 and 20. I make said dress parts unusually wide between the respective edges 19 and 20 and generally, without pleats or other folds. I may, under certain conditions, provide the blank with suitable tucks or pleats but will stitch these down so that they are flat and, in effect, do not change the character of 40 the blank as regards general flatness. The front part 17 comprises a skirt portion 21 and waist portion 22, and the back part 18 comprises a skirt portion 23 and an upper back portion 24. I further provide the fabric blank with short 45 sleeve portions 25 and cut an opening 26 in the blank to provide a head inserting opening having a front neck line 27 and a back neckline 28. The opening 26 may be variously shaped to provide desired forms of neckline and the sleeve portion 50 25 may also be varied in shape and length for various effects. I make the opening 26 relatively large and the line of the sleeve end relatively long for reasons later apparent.

The fabric blank which I provide is shown in 55 Fig. 3. It will be noted that the waist lines of

both the front and back parts 17 and 18 are somewhat narrower than the remaining portions of the blank, so that the skirt portions 21 and 23 are flared from the waistline outwardly and downwardly toward the blank ends 21^a and 23^a, respectively, and so that the waist and upper back portions 22 and 24 are flared outwardly and upwardly toward the sleeves 25. It will be further noted that the sleeve ends are formed on a reentrant curve to provide concave indentations 25^a.

On the fabric blank which I have provided and along the waistline thereof between the front, skirt and waist portions 21 and 22, I provide the tape 11 which extends from side to side of the dress front and in an arc substantially paralleling the blank end 21^a. I provide similar tapes 12 and 13 around the neckline 27 and 28 and along the ends of the sleeve portions 25, respectively. In practice, I stitch said tapes 11, 12 and 13 to the fabric along spaced lines of stitching 29 and 30 to provide pockets or channels 31 between the lines of stitching in one direction and between the various tapes and fabric blank in the other. I prefer to interrupt the tape 12 at the middle front of the neckline at 32 to provide an entrance slit for the string 15 which extends through the pocket formed by said tape 12. I make said string 15 of sufficient length so that both its ends project from said slit 32. I provide a similar interrupting slit 33 at the midpoints of the tapes 13 which are stitched along the sleeve edges. I may, in practice, provide two such slits 32 or 33 in side by side relation and form said slits as either round or elongated eyelets through which the ends of the string 15 project.

However, before I insert the strings 14, 15 and 16 into the pockets of the respective tapes 11, 12 and 13, I sew the front and back parts 17 and 18 of the fabric blank together along the related side edges 19 and 20 of said parts to form said blank into a flat loosely shaped dress in which the waistline and neck and sleeve openings are abnormally large. The side seams thus provided extend from the bottom of the dress to the points 34 defining the sleeve openings. With the dress thus provided I insert the string 15 around the neckline as set forth above, I insert the string 16 into the pockets formed by the tapes 13 along the sleeve ends in a similar manner, and pass the string 14 through the pocket formed by the tape along the front waistline.

I have shown the drawstring 14 as disposed in the channel formed along the front waistline and adapted to be tied around the back of the garment. I may, in practice, provide two drawstrings in front and back waist channels and tie the respective ends of these strings at either or at both the sides of the garment. In this case I would provide a tape similar to the tape 11 along the waistline of the back of the garment.

The modification shown in Fig. 5 illustrates another manner of forming the various string receiving channels of the garment. As shown, the channels may be formed by doubling back the garment fabric as at 40 and stitching at 29^a and 30^a to form the channel 31^a similar to the channel 31.

The tape which I employ in my invention is known as bias cut tape and I prefer to use this type of tape so that the same can be stitched into place around the various curves of the waistline, neckline and sleeve ends in a flat conforming con-

dition. However, I desire to depart from using conventional bias cut tape and to use instead, embroidered, printed, or otherwise decorated bias cut tape which, in addition to its functional properties, is decorative and pleasing to the eye. The numeral 35 indicates such decorations. I have shown the tapes applied on the outside of the dress. If desired, said tapes may be stitched on the inside thereof.

It will be seen that I have provided a simple, flat dress which is, generally, loosely shaped. The dress can easily be donned by passing the same over the head of the wearer and by inserting the arms through the sleeve openings. Donning and removing the dress is more easily accomplished by reason of the large neck and sleeve openings which I have provided by my construction. With the dress on the body of the wearer, the ends of the string 14 can be passed around the back and tied. In doing this the waistline at the tape 35 can be Shirred, gathered or otherwise arranged according to the size of the wearer's waistline. Fig. 2 shows this condition and further indicates, by comparison with Fig. 1, how the drawstring action of my construction provides for a variable or adjustable fit of the waistline of the dress. The neckline can also be gathered and crimped by the string 15 in a similar manner, and a bow tied in said string to additionally enhance the appearance of the dress. The foregoing also applies to the sleeve ends which can be Shirred and puckered by drawing up on the string 16. The indentations 25^a of the sleeve ends, now become effective to provide a full and pleasing puff in the upper sleeve part as shown at 25^b. This is attained by the variation in sleeve length from the neck opening to the reentrantly curved sleeve end.

Washing and ironing the dress is easily accomplished. Tedious and expensive hand ironing is obviated since the dress can be passed through a mangle in its normal flat condition and be perfectly ironed thereby in a small fraction of the time necessary for hand ironing. Accordingly, my invention is particularly adapted to be used for providing children's dresses, house dresses, many types of feminine uniforms, and like garments.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A garment comprising a single continuous flat elongate fabric blank having front and back portions extending in opposite directions from the middle portion of the blank, having sleeve portions projecting laterally from the middle portion of the blank, and having a neckline defining an opening and located between the sleeve portions, a tape stitched along the waistline of the garment, a tape stitched substantially entirely around said neckline, a tape stitched around the ends of said sleeve portions, all of the said tapes forming channel pockets, and drawstrings in the channel pockets for gathering together the portions of the garment along which said tapes are stitched gathering the garment at said waistline, the neckline and the sleeve ends.

2. A garment comprising a single continuous flat elongate fabric blank having front and back portions extending in opposite directions from a

middle portion and each reduced in width at the waist portion of the garment and flaring from the waist portion to the ends of the blank which are curved to define the bottom edge of the garment, the blank having sleeve portions projecting laterally from said middle portion and the blank having an opening in the middle portion between the sleeve portions defining a curved neckline, tapes stitched along the waistline of the garment, a tape stitched to the middle portion of the blank substantially entirely around said neckline, tapes stitched along the ends of said sleeve portions, all of the said tapes forming channel pockets, and drawstrings in the channel pockets gathering together the portions of the garment along which said tapes are stitched shaping the garment at the waistline, the neckline and at the sleeve ends.

3. A garment comprising a single continuous flat elongate fabric blank having front and back portions extending in opposite directions from a middle portion and each reduced in width at the waist portion of the garment and flaring from the waist portion to the ends of the blank which are curved to define the bottom edge of the garment, the blank having sleeve portions projecting laterally from said middle portion and having curved outer edges and the blank having an open-

15

20

25

ing in the middle portion between the sleeve portions defining a curved neckline, tapes stitched along the waistline of the garment, a tape stitched to the middle portion of the blank substantially entirely around said neckline, tapes stitched along the ends of said sleeve portions, all of the said tapes forming channel pockets, and drawstrings in the channel pockets gathering together the portions of the garment along which said tapes are stitched shaping the garment at the waistline, the neckline and at the sleeve ends, the tapes being bias cut decorated tapes having interrupting cuts through which the ends of the draw strings project.
